UNITED STATES PATENT OFFICE

2,664,313

FUEL INJECTION APPARATUS FOR
INJECTION ENGINES

Tsurukichi Ono, Fukushima-Ken, Japan

Application July 28, 1950, Serial No. 176,396

3 Claims. (Cl. 299—107.6)

1

This invention relates to improvements in fuel injection apparatus for an injection engine, such as diesel engine, and more particularly to the structural details of a needle valve therefor, the valve comprising two elements namely a valve body and its push rod which serves to keep said valve pressed against its seat correctly.

It is a particular object of the invention to provide a fuel injection assembly wherein the needle valve has a regular contact with its valve seat during operation. It is a further object of the invention to provide a fuel injection apparatus for a diesel engine, wherein the fuel is atomized completely thus increasing materially the efficiency of the engine. It is still a further object of the invention to provide a fuel injection apparatus for an injection engine, which is of sturdy construction and which will last much longer than conventional fuel injection apparatus.

The present invention offers a solution of the partial defacement problems of the needle valve and the valve seat. In accordance with the present invention no side pressure occurs between the sliding member and its guide member, namely, the needle valve spindle and its guide, and as the result, the partial defacements of the needle valve and its seat which above mentioned, are positively prevented.

The novel features which we believe to be characteristic of this invention are set forth with particularity in the appended claims. This invention itself both as to its construction and function may be understood by reference to the following description taken in connection with the accompanying drawing in which:

Figure 1 is a longitudinal sectional view of a constructional form of fuel injection apparatus embodying this invention.

Figure 2 is a transversal sectional view taken on the line A—A of Fig. 1.

Figure 3 is a longitudinal sectional view of another modification of this invention.

Referring to Figs. 1 and 2, 1 is the valve housing having a longitudinal bore 2 and a valve spindle 3 is slidably mounted within the bore. The spindle 3 terminates in a needle valve head 4 which cooperates with a seat 5 provided in the valve housing. At the bottom of the housing 1, a fuel chamber 6 communicates with the bore 2 at the lower end of the bore. Fuel injection apertures or holes 7 lead from the space below the seat 5 to a point externally of the housing 1. The fuel may be supplied to the chamber 6 through conduits 8 by the use of any suitable type of fuel pump (not illustrated).

2

Along its central axis, the spindle 3 is formed with a longitudinal bore 9 which terminates at its lower end in a concave surface 10 and the angle of the surface is preferably about 120 degrees. The upper end of the bore is provided with a screw-threaded section 11, by means of which the valve spindle may be removed from the bore 2, when desired. Any convenient type of threaded bar may be employed to engage the threaded section 11.

In the bore of valve spindle 3 a push rod 12 is inserted loosely, and the push rod 12 has a conical lower end 13 supported on the bottom of said bore 9 by its conical end. The end 13 of the push rod engages the surface 10 in the bore 9 and the angle of the end 13 is approximately 60 degrees.

Therefore, it will be seen that the axis of the push rod coincides exactly with the axis of needle valve and the contacting points of the members will be on said coincided axis. The push rod 12 is provided with an area 14 of enlarged diameter near the upper end and the periphery of the area 14 slidably engages the wall of the bore 2 at a point above the spindle 3. At its upper end the push rod is pressed downwardly by a spring as is customary in the art. The spring, through the push rod serves to maintain the valve 4 against the seat 5. The pressure of the spring is less than that of the fuel which is forced into the chamber through the conduits 8.

So when the fuel pump is in action and the compressed fuel has been forced into the fuel chamber through the conduits 8, the needle valve will be lifted from the valve seat upwardly against said spring action, and then the fuel will be injected out from the injection holes 7 in an atomized state. When the fuel pump has stopped, however, the spring action overcomes the pressure of fuel chamber, so the push rod thrusts the valve spindle through its end 13 resting on the surface 10 of the bore of the spindle thereby urging the valve against its seat.

In accordance with the present invention, the needle valve is pressed on the valve seat only by the conical end 13 of push rod which contacts with said valve at its concaved conical surface 10, and as their contact point is on the coincided axis of these two members, the needle valve will fit in its seat exactly.

In conventional apparatus, a single valve spindle is used and it terminates in a valve head and spring means cooperates with the upper end of the spindle to maintain the head against its seat. Thus, a certain amount of side pressure

acts upon the spindle when the valve head is moved toward its seat and this pressure is due to the clearance existing between the spindle surface and the inside surface of the bore. This side pressure causes wearing of the spindle, the needle valve and particularly the valve seat.

It is a matter of common knowledge that the partial defacements of the valve and valve seat causes many undesirable phenomena for the injection device, such as supplying unatomized fuel to engine, difficulty of repairs and lack of durability etc.

With the present invention, these side pressures do not occur since the spring pressure thrusts only the push rod and the end of the rod 15 presses the valve spindle and as previously mentioned, the contact point between the rod and the spindle is on the same central axis of the members.

Therefore, even though the push rod has inclined and diverted from the axis of valve spindle by the spring pressure, no side pressure takes place between the valve spindle and its bore or the needle valve and its seat because of the self centering action which has occurred by cooperative functions of said conical end and said concaved conical surface. The results of an experiment of comparative test has indicated that the present invention was vastly superior to any old type devices in the function of fuel atomization and its durability.

One of the modifications of this invention is shown in Fig. 3, in which a steel ball 15 is lodged between the lower end 13 of the push rod and the bottom surface 10 of the bore 9. These contacting surfaces which hold the steel ball 15 are both of concave configuration and their angles are about 120°.

The invention is not limited to the constructional form here shown and described which is, 40 as above stated, given only by way of example, as the invention may be performed in other ways, without departing from its principle. I claim:

1. In a fuel injection assemblage for internal 45 combustion engines, a valve body having a fuel chamber therein, means defining a fuel feed conduit in the body leading from a supply source to the fuel chamber, fuel discharge ports in the body below said chamber and in communication therewith, further means defining an inverted frusto-conical valve seat in the body intermediate the fuel chamber and the discharge ports, a

bore extending longitudinally of the body from one end of the body and merging with the fuel chamber, a valve spindle lodged in and reciprocable in said bore, a conical head on said spindle 5 adapted to cooperate with the wall of the valve seat to open and close communication between the fuel chamber and the discharge ports, the said valve spindle being provided with a bore extending longitudinally from the end remote from the conical head and terminating in a seat, a push rod slidably mounted within the spindle bore with the axis of the push rod coinciding with the axis of the valve spindle, a spherical object lodged between the inner end of the push rod and the seat in said spindle defining a contact area between the push rod and the valve spindle falling on the axis of the push rod and the spindle, an enlarged area on the said push rod at a point above the valve spindle of the same diameter as the outer diameter of the valve spindle slidably engaging the wall of the bore in said body to guide the push rod within the spindle bore, and means operatively associated with said push rod to maintain the conical head of the valve spindle normally in engagement with the frusto-conical seat.

2. A fuel injection assemblage as defined in and claimed by claim 1 further characterized in that said spherical object is a steel ball.

3. A fuel injection assemblage as defined in and claimed by claim 1 further characterized in that said push rod is provided with a concave depression in the end thereof and the valve spindle is provided with a concave seat, the spherical object being lodged between said depression and concave seat.

TSURUKICHI ONO.
